UNITED STATES PATENT OFFICE.

JAMES DELL, OF SAN FRANCISCO, CALIFORNIA.

INJECTOR INSTRUMENT.

Application filed March 7, 1921. Serial No. 450,256.

To all whom it may concern:

Be it known that I, JAMES DELL, a subject of Greece, residing at the city and county of San Francisco and State of California, have invented certain new and useful Improvements in Injector Instruments, whereof the following is a specification.

This invention relates to injector instruments, for injecting liquids into otherwise more or less inaccessible places, such as injecting liquid medicaments into the 10 orifices of the body, for therapeutic purposes.

In general, the instrument consists in a hollow cylindrical body, having a solid head 15 with a channel therethrough connecting the hollow with the outer space. This body is made of a compressible material, such as rubber, and is encased in a resistant or stiff casing. Inside the casing is a compression 20 plate, and the casing is provided with an aperture for the thumb of the user, who presses in the compression plate and thereby squeezes the compressible body and determines the exudation of its contents, to 25 any desired degree. A slideable sleeve is applied to the casing, to protect the thumb aperture, and the compression plate. A cap is applied to the end of the sleeve, through which the head projects, to protect the latter when not in use, and this cap has a plug 30 adapted to enter the channel through the head, and plug the same, when the cap is in place, thus effectively preventing any undesired exudation of the contents of the 35 cylinder.

In the accompanying one sheet of drawing I have shown an instrument containing my invention.

Figure 1 is a perspective view of the 40 complete instrument, ready for use, the cap and the sleeve being in dotted lines.

Figure 2 is a longitudinal section view, showing the complete instrument, with all the parts assembled.

Figure 3 is a cross-section on the line 45 3. 3. of Figure 2.

In the figures:—The numeral 1 represents a hollow cylindrical body, composed of rubber, or other compressible material, closed 50 at one end by the, preferably integral, end wall 2, and at the other end by the tapered head 3. The head 3 is bored by a channel 4, through which liquid may be gotten into or out of the interior of the body 1.

The body 1 is enclosed in a casing 5, preferably of metal, covering the cylindrical

portion, and the back of the cylinder, and extending to the head 3, but not covering the latter. The back end of the casing may be flanged outward, or provided with a collar as at 6, to furnish a stop for the sleeve, presently to be described. At 7 is an orifice in the side of the casing 5, extending partly around the same, as shown in Figure 1 and by dotted lines in Figure 2. This orifice is 60 covered by a sleeve 8, when the instrument is out of use, which sleeve may slide along the casing, to uncover said orifice when it is desired to use the instrument.

Within the casing 5, and resting against the cylindrical body 1, is a presser plate 9, pressure upon which serves to compress the body 1, and cause the contents thereof to exude through the channel 4 in head 3. The plate 9 may be provided with an upstanding 70 portion 10, projecting into orifice 7, and adapted to be engaged by the thumb of the operator, and serving also to position the plate with respect to the other members of the instrument.

Casing 5 is provided, at its open end, with a cap 11, for the protection of head 3, which cap is removed when the instrument is to be used. The cap may be perforated, as at 12, to prevent atmospheric resistance to its displacement or removal. The cap is provided with a plug 13, adapted to act as a valve in closing channel 4, when the cap is in place, and a stopper 14 secured around the casing 5.

Having thus described my invention, and an embodiment of it, in the full, clear and exact terms required by law, and knowing that it comprises novel, useful and valuable improvements in the art to which it pertains, I here state that I do not wish to be limited to the precise construction and arrangement of the several parts, as herein set forth, as the same may be variously modified by a skilled mechanic without departing from the 95 spirit of the invention.

What I claim and desire to secure by Letters Patent of the United States, is the following, to wit:

1. An injector instrument, comprising, in 105 combination, a cylinder having a closed chamber therein and a tapered head at one end thereof, said head being perforated, a casing for said cylinder, having an orifice, means in said orifice for compressing said cylinder and causing the exudation of liquid within said chamber, and means for cover- 110

ing said orifice and preventing thereby accidental operation of said compressing means.

2. An injector instrument, comprising, in combination, a hollow flexible cylinder, having a closed end, and a perforated head at its opposite end, a casing for said cylinder, means through said casing for compressing said cylinder and causing the exudation of liquid therefrom, means engaging freely said casing provided with a plug adapted to close said perforation on said head, and means to cover said compressing means.

3. An injector instrument, comprising, in combination, a closed hollow body having a perforated head, a casing for said body and a removable cap for said head engaging freely said casing, a plug on said cap projecting into said perforation in said head and adapted to close the same, said casing having an orifice, means in said orifice permitting finger pressure upon said body, and causing thereby the exudation of liquid therein and a sleeve on said casing adapted to cover said orifice.

25 4. An injector instrument, comprising, in combination, a closed hollow cylindrical body, having a perforated head, a casing for

said body and a removable cap for said head, said casing having an orifice, a finger plate registering with said orifice adapted to transmit pressure to said body, means to close said orifice and a plug projecting from said cap to close said perforation on said head.

5. An injector instrument, comprising, in combination, a closed hollow cylinder adapted to contain liquid, said cylinder having at one end a tapered and perforated head, a casing enclosing said cylinder and adapted to protect the same, said casing having a thumb orifice extending partly around its side, a pressure plate registering with said orifice and adapted to transmit pressure to said cylinder, a sleeve, slidable upon said casing and adapted to cover said orifice, a cap applied to the head end of said casing, and adapted to cover said head, said cap provided with valve means projecting in said perforation of the head and close the same when not in use.

In testimony that I claim the foregoing I have hereto set my hand this 1st day of March, 1921.

JAMES DELL.
